CLAIM

We claim the ornamental design for an EFI throttle body, as shown and described.

DESCRIPTION

FIG. 1 is a front perspective view of an EFI throttle body showing my new design.

FIG. 2 is a front elevational view thereof;

FIG. 3 is a back elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a rear elevational view thereof.

The broken lines in the drawings illustrate unclaimed environmental structure as well as the boundaries of the claimed design. The broken lines, as well as the boundaries and structure they depict, form no part of the claimed design.
